UNITED STATES PATENT OFFICE.

THOMAS B. JEFFERY, OF CHICAGO, ILLINOIS.

DESIGN FOR A BICYCLE FORK-HEAD AND REINFORCE.

SPECIFICATION forming part of Design No. 28,401, dated March 22, 1898.

Application filed December 13, 1897. Serial No. 661,753. Term of patent 7 years.

To all whom it may concern:

Be it known that I, THOMAS B. JEFFERY, a citizen of the United States, residing at Chicago, county of Cook, and State of Illinois, have invented and produced a new and original Design for a Bicycle Fork-Head and Reinforce, which is fully set forth in the following specification, reference being had to the accompanying drawings, forming a part thereof.

This design relates to the fitting known as a "bicycle fork-head," which comprises extensions known as "fork-arm reinforces."

In the drawing, which is a perspective view, A A are rounded shoulders, and A' a swelled center of the head, and B B the reinforces by whose shape and appearance the design is

characterized. This shape or appearance is that of a conventional spear or arrow pointing downward, having lateral projections back of the point.

20

I claim—

The design for a bicycle fork-head and reinforce herein shown and described.

In testimony whereof I have hereunto set my hand, in the presence of two witnesses, at 25 Chicago, Illinois, this 20th day of November, 1897.

THOS. B. JEFFERY.
